UNITED STATES PATENT OFFICE.

FRANK M. FREDERICK, OF FAIRBURY, NEBRASKA.

RELEASE VALVE FOR AIR-BRAKE SYSTEMS.

Application filed August 8, 1921. Serial No. 490,623.

To all whom it may concern:

Be it known that I, FRANK M. FREDERICK, a citizen of the United States, residing at Fairbury, in the county of Jefferson and 5 State of Nebraska, have invented certain new and useful Improvements in Release Valves for Air-Brake Systems, of which the following is a specification.

This invention relates to improvements in 10 release valves, for use on auxiliary reservoirs of air brake systems.

The primary object of the invention is the provision of an improved release valve for use on railway cars, and which can be mechanically set in a fixed open position for 15 exhausting air from a reservoir, requiring but little of an operator's time; in this respect differentiating from the present type of standard release valve, wherein the same is 20 manually held open until the air has been entirely exhausted from the auxiliary reservoir.

A further object of the improved release valve is the provision of one which utilizes certain features of the standard type, including 25 a novel arrangement for maintaining the same in open position to effect the above mentioned results.

A further object of the invention is the provision of a release valve which is simple 30 in construction, durable, and one which is positive in operation.

Other objects and advantages will be apparent during the course of the following detailed description.

35 In the accompanying drawings, forming a part of this specification, and in which similar reference characters designate corresponding parts throughout the several views,

40 Figure 1 is a fragmentary end elevation of a car, showing an auxiliary tank attached thereto, and embodying the improved release air valve.

Figure 2 is a side elevation of the improved release valve, showing operating mechanism thereof.

Figure 3 is a cross sectional view through the improved release valve, taken on the line 3—3 of Figure 2.

50 Figure 4 is a perspective view of the valve operating mechanism, and showing the position assumed by the improved device, when the valve is in closed position.

Figure 5 is a perspective view of the operating mechanism illustrated in Figure 4,

showing the position the same assumes when the valve is open.

In the drawing, wherein for the purpose of illustration is shown the preferred embodiment of my invention, the letter A designates 60 a car of any approved construction, having the ordinary auxiliary air reservoir B mounted thereon. The improved valve structure C is provided as a release device, whereby the air can be conveniently exhausted 65 from the reservoir B. For conveniently designating the various parts of the improved valve C, the same may be subdivided into that portion D which is at present used in connection with the standard type of release valve now in common use; the letter E designating the novel operating means used in connection with the mechanism D to form the improved valve C.

The standard type of release valve, in 75 which is included the mechanism D, preferably comprises the attaching stud 10, including the polygonal nut portion 11, and the screw threaded attaching stem 12, for detachable connection in the auxiliary reservoir B. A bore 13 is provided, through the stud 10. The cylinder body 14 of the standard equipment E detachably receives the screw threaded end 15 of the stud 10, and is provided with a valve seat 16 therein 80 having a bore therethrough, provided with radial apertures 17 for air exhaustion. The vent valve 18, as part of the equipment D, preferably includes a plunger 19, having a valve head 20 thereon provided with a gasket 21 therein for engaging upon the valve seat 16, for closing the bore therein to seal the same from communication with the bore 13 in the stud 10, and consequently preventing 85 passage of air from the auxiliary reservoir B for exhaustion purposes. A spiral spring 25 is ordinarily provided in the device D, and engaging the head 20, and a portion of the stud 10 for normally forcing the gasket 21 into engagement with the seat 16 for retaining compressed air in the auxiliary reservoir B. A bearing head 26 is ordinarily provided as part of the standard means C, for engaging the plunger 19 for forcing the same to open the valve structure 90 18.

Referring to the improved operating means E, a bearing plate 30 is bolted, as at 31 in detachable manner upon the flattened side of the cylinder 14, and on an end of 110

said cylinder 14 remote from the stud 10. A pair of spaced lugs 32 are provided, extending outwardly at right angles from the plane of the plate 30, and having aligning apertures therein, for detachable reception of a bolt 33.

A two way operating lever 35, is pivotally mounted upon a detachable screw 36, which engages through the plate 30 and into the cylinder 14, immediately over the lugs 32. From the pivot point as defined by the screw 36, the lever 35 is provided with a pair of oppositely extending arms 37 and 38, which extend upwardly away from the pivot 36, and outwardly from the side of the cylinder 14. The operating lever 35 is provided, at the point of juncture of the arms 37 and 38, and upon the outer surface 39 thereof, with a cam projection 41. The projection 41 extends longitudinally in a direction transverse to the axis defined by the release valve C. and is centrally provided with a depression 42. Projection pins 43 and 44 are provided, extending outwardly from the extreme end portions of the cam projection 41, and respectively adjacent the arms 37 and 38. Each of the pins 43 and 44 are provided with a flat surface 45 facing the depression 42 in the cam projection 41. The depression 42 in cam 41 inclines gradually upwardly toward the pins 43 and 44.

A second lever 46, substantially J-shaped in formation is provided as part of the operating mechanism E, having the longer leg 47 provided with an aperture 48 transversely therethrough, and adapted for pivotally receiving the detachable screw 33, whereby said lever may be oscillatively mounted to the lugs 32. In this position, the shorter leg or hook 49 of the lever 46, projects beneath the cylinder 14 of the release valve C and engages the bearing plate 26 of the mechanism D. The longer leg 47 overlies the outer surface 39 of the two way operating lever 35, and engages at its extreme upper end 49 against the cam projection 41.

The release valve C is assembled in the auxiliary reservoir B, in such manner that the two way operating lever 35, extends longitudinally in a direction transversely of the car A. Operating rods 50 and 51 may be pivotally attached as at 52 to the ends of the arms 37 and 38; the extreme outer end 55 of the operating rods 50 and 51 being supported by suitable brackets 53 carried adjacent the lower longitudinal edges of the car A.

In normal position, with the auxiliary air tank B, filled with compressed air, the valve head 20 is of course seated in the cylinder 14. In this position, the plunger 19 forces the second lever 46 of the means E outwardly, in such manner upon its pivot 33 that the extreme upper end 49 thereof engages in the

depression 42 of the cam projection 41. When the valve mechanism 18 is so closed, the two way operating lever 35 is of course symmetrically disposed on the bearing plate 30, in such manner that the cam projection 41 properly receives the lever 46. When it is desired to release the air from the auxiliary reservoir B, as is the case when the car is on the siding, or standing still awaiting repairs, the operator either pulls outwardly or pushes inwardly upon either of the operating rods 50 or 51, to rock the two way lever 35 upon its pivot pin 36. As the lever 35 is rocked, the extreme end 49 of the lever 46 is forced outwardly by riding over the inclined face adjacent the depression 42, until the operator has oscillated the lever 35, until the flat faces 45 of one of the projections 43 or 44 engages the side of the lever 46. By this operation, the lever 46 is rocked upon its pivot 33, and the end of the shorter arm 49 thereof pushes inwardly upon the bearing plate 26, to force the plunger 19 of the mechanism D inwardly to unseat the valve structure 18, whereby air may escape from the reservoir B outwardly, through the cylinder 14.

The lever 35 can, of course, be operated by means of arms 37 or 38 to open the valve mechanism 17. The pins 43 and 44 of course define the limits of oscillation of the lever 35 and determine the open position of said valve mechanism. Due to the flat surfaces 55 adjacent the pins 43 and 44, the lever 46 when once positioned to open the valve mechanism 17 may be maintained in fixed position, independent of manual holding of the same, to exhaust air from the reservoir B.

From the foregoing, it can be seen that a release valve has been provided, in which it is merely necessary for an operator to rock the lever 35 to oscillate the lever 46 for opening the valve mechanism 18, after which the lever 46 by resting upon either of the flat surfaces 55 of the cam projection 41, is maintained in fixed position for opening the valve head 20, against tension of the spring 19. Many cars A are shifted at one time, into a terminal. Preparatory to detachment of the train and to individual shifting of the cars A, the air should be released from the auxiliary reservoir B. It can be seen what a problem this becomes when there are a great many of the cars A in a train; and as is well known, with the present type of release valve, the operator is forced to hold the lever of the same open, until all of the air is exhausted from the reservoir B. In contra-distinction to this cumbersome method of releasing air from the reservoirs B, applicant's release valve merely has to be set in open position, by an inspector or operator passing along one side of the train and pulling outwardly or pushing inwardly upon either of the operating rods 50 or 51, 130

to open the valve structure 18 for release of air. Many cars A can thus be done in the time that it takes a single reservoir B to exhaust the air therein to the release valve.

- 5 5. An operator or inspector so releasing the air from the reservoir B in a long train, can pass down one side opening the various release valves C, and upwardly on the other side of the train to close the valve mechanism 18, 10 by properly rocking the various levers 35, until the lever 46 is in proper position in the depression 42. When this operation has been done to a long train, the train is in condition ready for a shifting crew.
- 15 15. Various changes in the shape, size and arrangement of parts, may of course be made to the form of the invention herein shown and described, without departing from the spirit of the invention or the scope of the 20 claims.

I claim:

1. A release valve for air brake systems comprising in combination a cylinder, a vent valve mechanism, a lever, and sliding cam means for receiving said lever thereagainst to rock said lever to maintain the same in position for holding the vent valve mechanism open.

2. A release valve, comprising in combination a cylinder, a vent valve mechanism,

a lever in operating engagement with said vent valve mechanism, a second lever, cam means on said second lever for engaging against said first mentioned lever to selectively maintain the vent valve mechanism 35 open or permit the same to assume a closed position.

3. In a device of the class described, the combination with the cylinder and vent valve mechanism of a standard air brake release valve, of a plate mounted on said cylinder, and means mounted on said plate for engaging said vent valve mechanism for operation to assume a set position to fix said vent valve in open position. 45

4. In a device of the class described, the combination of a cylinder, a valve mechanism in said cylinder, a plate detachably mounted on said cylinder, a lever oscillatively mounted on said plate and maintained 50 in outward forced position by said valve mechanism, a second lever pivotally mounted on said plate and including a cam arrangement for cooperation with said first mentioned lever to force said first mentioned lever for oscillation upon its pivot and against action of said valve mechanism to maintain said valve mechanism in fixed open position. 55

FRANK M. FREDERICK.
